UNITED STATES PATENT OFFICE.

BERNHARD URBAND, OF NEW YORK, N. Y.

TRAVELING-BAG.

1,277,785.

Specification of Letters Patent. Patented Sept. 3, 1918.

Application filed January 17, 1918. Serial No. 212,218.

To all whom it may concern:

Be it known that I, BERNHARD URBAND, a citizen of the United States of America, residing at New York city, Bronx county, 5 State of New York, have invented certain new and useful Improvements in Traveling-Bags, of which the following is a full, clear, and exact description.

This invention relates to improvements 10 in identification tabs for traveling bags, suit-cases and the like, the object of the invention being to provide a tab having a pocket to receive a card containing the address of the owner of the satchel or the like 15 or any other indication of ownership, and in combination with the tab, I provide a protecting cover for the tab, the tab and its cover preferably consisting of (in this instance) two separate and distinct elements 20 which are secured, independently of each other, to their respective separably connected satchel-members. The tab and its cover are preferably secured, at one end thereof, to their respective separably connected 25 members adjacent the lock for said members, and at opposite sides thereof. When the tab and its cover are secured together, the said cover will overlap the lock; hence said lock cannot be reached for the 30 insertion of a key and the metal of the lock will be protected against rain and injury. The tab and its cover, can be used to separate the separably connected satchel members after they have been unlocked.

35 I will now proceed to describe my invention in detail, the novel features of which I will point out in the appended claims, reference being had to the accompanying drawing, wherein:—

40 Figure 1 is a perspective view of a portion of a bag or satchel embodying my improvement;

Fig. 2 is a cross sectional view thereof, the tab and its cover being illustrated as connected; and

45 Fig. 3 is a plan view of the device as illustrated in Fig. 1, the tab-cover being broken off.

In Fig. 1 the numerals 4 and 5 indicate 50 the separably connected members of a satchel or the like, provided with a lock 6 to connect same. The numeral 7 indicates a tab consisting of (in this instance) two laminations or members 8 and 9 stitched together 55 at 10 to provide a pocket 11 to receive a card

12 or the like. The tab 7 is provided, at one end, with a member 13 of a fastening device, a snap-socket for instance, the opposite end of said tab being secured to the satchel member 5, as at 14, by sewing, riveting or otherwise. The other element of my improvement consists of a cover 15 having at one end a fastening-member 16 to co-operate with the member 13, a button for instance. The opposite end of the cover 15 is 60 secured in any desirable manner to the satchel-member 4.

65 It will be seen that the tab and cover are separate members independently secured to the satchel. As can be seen in Fig. 2, the 70 cover 15 will overlap and conceal the lock 6 when said cover 15 and tab 7 are secured together. When positioned as indicated in Fig. 1, the tab and its cover may be used as handles to pull the satchel members 4 and 5 75 apart, after they have been unlocked. The cover 15 also serves to protect the identification card or its transparent covering 18. When roughly handled or packed with other articles, the identifying cards, usually employed, become damaged or entirely destroyed, for the reason that they are not protected and are usually rigidly secured to the bags or satchels. As the tab 7 is more 80 or less flexible, it will, to a large extent, resist rough handling, as it will yield, should it come in contact with other articles, especially if the satchel is tossed into a car or baggage-room or upon a truck.

85 What I claim as my invention is:

90 1. In combination with a bag or the like, a flexible identification tab secured at one end thereof to one of the separably connected members of the bag, and a flexible cover secured at one end thereof to the other 95 member of the bag, and means to secure the identification tab and its cover together, the identification tab and the cover therefor when separated also serving as handles to pull the bag-members apart.

100 2. In combination with a bag or the like having separably connected members, a lock to secure said members together, a flexible identification tab secured, at one end thereof, to one of said bag members at one side of the lock therefor, a cover for the lock and tab, secured at one end thereof to the other bag member at the opposite side of the lock, and means to secure the identification tab 105 and its cover together, said cover being 110

arranged to overlap the lock when secured to said tab.

3. In combination with a bag having separably connected members, a lock therefor, an identification element carried by one of said members, a cover common to the lock and identification element carried by the other bag-member, and means to detachably secure the identification element and 10 cover together, the identification element and cover also serving as handles to pull the bag-members apart.

4. In combination with a bag having separably connected members, a lock for 15 same, a flexible tab secured to one of said

members provided with a pocket to receive a card or the like, a flexible cover for said tab secured to the other bag member, and means to secure the tab and its cover together at the free ends thereof, said tab and 20 cover being arranged to act as handles to separate the bag members when said tab and its cover are disconnected and the bag members are unlocked.

Signed at New York city, N. Y., this 15 25 day of January, 1918.

BERNHARD URBAND.
